UNITED STATES PATENT OFFICE.

SAMUEL G. GOSS, OF GLENCOE, ILLINOIS, ASSIGNOR TO THE GOSS PRINTING PRESS COMPANY, OF CHICAGO, ILLINOIS, A CORPORATION OF ILLINOIS.

PLATE-FINISHING MACHINE.

1,126,983.

Specification of Letters Patent.

Patented Feb. 2, 1915.

Application filed June 3, 1914. Serial No. 842,587.

To all whom it may concern:

Be it known that I, SAMUEL G. Goss, a citizen of the United States, residing at Glencoe, in the county of Cook, State of Illinois, have invented certain new and useful Improvements in Plate-Finishing Machines, of which the following is a specification, reference being had to the accompanying drawings.

10 My invention relates to plate finishing machines of the type employing a rotatable drum for carrying a printing plate into operative engagement with means for shaving the ribs on the inner face and for severing the tail and trimming the ends of the plate.

It is one of the objects of my invention to provide an automatically-acting plate-stop which shall prevent the insertion of a plate 20 into the drum until the plate previously acted upon has been fully withdrawn from the drum. In this way the plate-stop device, by which the plate is positioned in the drum in proper position for the trimming 25 operation, is given an opportunity to assume its normal operative position before the new plate is pushed into the drum.

It is another object of my invention to improve devices of this type in sundry details 30 hereinafter pointed out.

The means by which I have accomplished these objects are illustrated in the drawings and are hereinafter specifically described.

35 In the drawings,—Figure 1 is a central vertical section through a plate finishing machine embodying my improved plate-stop device, and adapted to be equipped with my improved drum-extending device; Fig. 40 2 is a side view of the drum shown in Fig. 1 equipped with my improvements; Fig. 3 is an end view of the parts shown in Fig. 2; Fig. 4 is an edge view of the means for extending the drum for trimming an eight- 45 column plate; Fig. 5 is a side view of the part shown in Fig. 4; and Fig. 6 is a central vertical section through one end of the drum, showing the drum-extending ring in position thereon.

50 Referring to the several figures of the drawings in which corresponding parts are indicated by the same reference characters,—10 indicates the framework of the machine having revolubly mounted thereon a drum 11 adapted to be rotated by means

of a worm 12 fixed upon a shaft 13 driven from any suitable source of power, the worm 12 meshing with a worm gear 14 loosely mounted upon the drum 11 and adapted to be secured thereto when desired 60 for the rotation of the drum. At the plate receiving end of the drum 11 is located a standard 15 adapted to have slidably mounted thereon a printing plate 16 in alinement with suitable supports 17—18 mounted upon 65 the inner face of the drum 11 whereby a plate is adapted to be slid from the standard 15 into position in the drum. Extending into the drum 11 from its front end is a bracket 19 suitably supported from the 70 framework 10, said bracket being provided with guide-blocks 20—21 adapted to guide the plate being inserted into the drum. The bracket 19 is also provided with a suitable shaving knife 22 at one side and a mangler 75 23 at the opposite side. A shield 24 is provided in connection with the means for locking the plate in the drum for preventing the accumulation of chips and shavings therein. No claim is made herein to the 80 mangler 23 or the shield 24 inasmuch as these devices are the invention of Joseph J. Walser, and are covered by his application for patent thereon, filed June 3, 1914, Serial No. 842,579.

85 25 indicates a plate-stop device mounted upon the bracket 19 controlled by a lever 26 extending to the rear end of the drum 11. As shown in Fig. 1, the plate-stop device 25 is shown as serving to stop a plate 27 in 90 proper position in the drum 11 prior to the locking of the plate in the drum. No claim is made herein to the plate-stop device 25—26 inasmuch as this device is the invention of William Evensen covered by his 95 application for patent thereon, filed June 3, 1914, Serial No. 842,591.

28 indicates a rotary brush of any suitable type adapted to be rotated by means of a gear 29 meshing with a gear 30 which is 100 driven from any suitable source of power. The brush 28 is located in front of the drum 11 in alinement therewith whereby the finished plate can be slid from the drum 11 along suitable slideways to cooling position 105 relative to the brush 28, a plate 31 being shown in position for cooling in Fig. 1. A plate is adapted to be moved from the finishing drum 11 into cooling position relative to the brush 28 by means of a jaw 32 110

reciprocated back and forth through the medium of a rack-bar 33 driven by a gear 34 mounted upon a shaft 35, in turn driven by a pinion 36 rotated by a segment 37 formed upon a bell-crank lever 38 swung 5 back and forth through the medium of a link 39 operated by a crank disk 40 mounted upon the shaft 41 driven from any suitable source of power. Inasmuch as the 10 parts so far described form of themselves no part of my present invention it is believed to be unnecessary to further describe them herein.

Coming now to my improved means for 15 preventing the insertion into the drum of a printing plate to be trimmed until after the printing plate which has just been trimmed has passed entirely out of contact with the drum, 42 indicates a bell-crank lever pivotally mounted upon a bracket 43 supported from the framework 10 and normally held turned in clockwise direction in Figs. 1 and 2 by means of a spring 42^a. At the lower end of one arm of the bell-crank lever 42 20 is revolvably mounted a roller 44 adapted to be contacted by a plate in the course of being withdrawn from the drum 11 for throwing the bell-crank lever 42 in counterclockwise direction in Fig. 1. Pivoted 25 connected to the upper end of the other arm of the bell-crank lever 42 is a rod 45 having a yielding pivotal connection at its rear end with the upper arm of another bell-crank lever 46 which is pivotally mounted 30 upon a bracket 47 depending from the slideway 48 through which the rack-bar 33 is reciprocated. The yielding connection between the rod 45 and the bell-crank lever 46 comprises a slot 45^a in which the pivot 35 pin 45^b works, said pivot pin being yieldingly held at the rear end of the slot by means of a spring 45^c bearing against a bearing block 45^d. The rear end of the 40 horizontally-extending arm of the bell-crank lever 46 is provided with a downwardly-turned end whereby when the bell-crank lever 42 is turned in counterclockwise direction in Fig. 1, as indicated in dotted lines therein, the turned end 49 stands 45 in the path of a printing plate to prevent its being slid from the standard 15 into position upon the supporting ribs 17-18 of the drum. In case a printing plate should be pushed under the downwardly-turned end 50 of the bell-crank lever 46 before a plate already in the shell or drum had been moved out, upon the engagement of the roller 44 by said plate when being withdrawn from the shell the lever 46 would be turned into 55 contact with the new printing plate about to be pushed into the drum but the spring 46^c would yield so as to prevent breakage of any of the parts.

As best shown in Figs. 1 and 6, the inner 60 face of the rear edge of the drum 11 is

rabbeted out to receive a correspondingly-shaped ring 50 extending from the front face of a drum-extending member 51, said member 51 being adapted to be secured in position upon the rear end of the drum by 70 means of screws 52 inserted in suitable registering openings in the member 51 and the drum 11. Revolvably mounted in the framework 10 at one side of the drum 11 is a shaft 53 having fixed upon its front end a 75 rotary cutter 54 adapted to trim the front end of the plate as it is carried by the drum past the rotary cutter, the shaft 53 being driven from any suitable source of power through the medium of the sprocket 80 gear 55 fixed upon the front end of the shaft 53. Mounted upon the rear end of the shaft 53 is a similar rotary cutter comprising a hub 56 having fixed thereon a disk 57 in which are removably mounted a 85 plurality of cutters 58. With the drum-extending member 51 in position upon the drum 11, as shown in Figs. 2 and 3, the hub 56 of the rearmost rotary cutter is placed upon the end of the shaft 53 and 90 secured in position thereon in the position shown in solid lines in Fig. 2. Upon the rotation of the drum 11, while at the same time the rotary cutters are being rotated, the plate is brought into the path of the 95 rotary cutters for the trimming and tail cutting operations, the plate being cut of a length longitudinally of the drum such as to accommodate eight columns. For the tail cutting operation the drum-extending 100 member 51 serves to support the rear end of the plate firmly in position adjacent to the rotary cutter so that it is impossible to twist or distort the plate. If it were desired to cut a plate of a length to accommodate seven columns, all that would be necessary to do preparatory to such operation would be to remove the member 51 and to turn the hub 56 of the rotary cutter end for end on the shaft 53, also removing the 110 blades 58 and turning them half way around so as to cut a beveled end at the rear of the plate instead of a square end.

What I claim as my invention and desire to secure by Letters Patent, is—

1. In a plate finishing machine, the combination of a shell, means coöperating with said shell for finishing a plate in position therein, and means for preventing the insertion of another plate into said shell in the course of the removal of a plate from said shell.

2. In a plate finishing machine, the combination of a shell, means coöperating with said shell for finishing a plate in position therein, and means for preventing the insertion of another plate into said shell from the rear end of the shell in the course of the removal of a plate from the front end thereof.

3. In a plate finishing machine, the combination of a shell, means coöperating with said shell for finishing a plate in position therein, and automatically-acting means for preventing the insertion of another plate into said shell in the course of the removal of a plate from the shell.

4. In a plate finishing machine, the combination of a shell, means coöperating with 10 said shell for finishing a plate in position therein, and means actuated by the removal of a plate from the shell for preventing the insertion of another plate therein.

5. In a plate finishing machine, the combination of a shell, means coöperating with 15 said shell for finishing a plate in position therein, a stop device at the rear end of said shell, and means actuated by the removal of a plate from the shell for moving said stop 20 device into position for preventing the insertion of another plate therein.

6. In a plate finishing machine, the combination of a shell, means coöperating with 25 said shell for finishing a plate in position therein, a lever pivotally mounted relative to said shell adapted to be turned down into position to prevent the insertion of a plate in said shell, and means actuated by the withdrawal of the plate from the shell for 30 moving said lever into plate stopping position.

7. In a plate finishing machine, the com-

bination of a shell, means coöperating with 35 said shell for finishing a plate in position therein, a plate stop device at the rear end of said shell, an arm extending normally into the path of a plate being removed from said shell and adapted to be displaced by the removal of the plate from the shell, and connections between said arm and said plate-stop device whereby upon the removal of a plate from the shell the plate-stop device is moved into operative plate-stopping position.

8. In a plate finishing machine, the combination of a shell, means coöperating with 40 said shell for finishing a plate in position therein, a plate-stop device at the rear end of said shell, a bell-crank lever at the front end of said shell, a roller carried by one 45 arm of said bell-crank lever standing normally in the path of a plate being removed from the shell, and connections between said bell-crank lever and said plate-stop device whereby the swinging of the bell-crank lever upon the removal of a plate from the shell serves to move said plate-stop device 50 into operative plate stopping position to prevent the insertion of another plate into the shell.
